His Attorney.

UNITED STATES PATENT OFFICE.

VINCENT M. MONTINGER, OF PITTSFIELD, MASSACHUSETTS, ASSIGNOR TO GENERAL ELECTRIC COMPANY, A CORPORATION OF NEW YORK.

STATIONARY INDUCTION APPARATUS.

Application filed June 13, 1921. Serial No. 477,021.

To all whom it may concern:

Be it known that I, VINCENT M. MONTINGER, a citizen of the United States, residing at Pittsfield, county of Berkshire, State 5 of Massachusetts, have invented certain new and useful Improvements in Stationary Induction Apparatus, of which the following is a specification.

My invention relates to stationary induction apparatus and has for its general object 10 an improved construction and arrangement of parts which is economical and readily manufactured.

More particularly my invention relates to 15 stationary induction apparatus of the portable shell type, a specific object being an improved housing adapted to support the winding terminals in a safe and accessible manner.

20 Small transformers and the like which are adapted for domestic use such as to operate toys, ring bells, light small lamps, etc., do not get the technical care and attention generally accorded to larger electrical apparatus. 25 Consequently it is necessary that this class of device should be made very rugged and as nearly foolproof as possible. The secondary terminals in particular should be made in a manner not easily knocked off, 30 nor easily disarranged, and disposed so that there is no uncertainty about the voltage across the connections which are made.

By my invention all these desiderata are 35 accomplished in a novel manner, and in a form which is compact and readily manufactured. In the practice of my invention I construct an end cap, such as are provided primarily to protect the ends of the windings which project from either end of the shell type core, with an insulating terminal board or bushing in which all the 40 terminals from the windings at that end are secured rigidly and in a manner not likely to be twisted loose from the winding leads.

45 For a more complete understanding of the nature and objects of my invention, reference should be had to the following detailed description taken in connection with the accompanying drawing in which:

50 Fig. 1 is a side view, parts being broken away, of a shell type transformer constructed in accordance with my invention; Fig. 2 is an end view in elevation of the same transformer; Fig. 3 shows the type of lamination employed; Fig. 4 shows an end cap

embodiment a modified form of my invention, while Figs. 5 and 6 show details.

Referring now to the drawing, 10 denotes a stack of shell type laminations aligned to form a core. A plan of these laminations is 60 shown in Fig. 3, and comprises an outer or yoke member 11 having a separable inner member 12 which, when formed into a stack with other inner members, provides a winding leg adapted to carry the primary and 65 secondary windings 13. The assembled inner members with the windings 13 thereon are pressed into the assembled outer members to form the transformer proper.

Over the ends of the windings 13 are provided the end caps 14 and 15 which are secured in place by the assembly bolts 16 which pass through the perforations 17 at each side of the laminations 10 as shown in Fig. 3 and through corresponding perforations 18 in the end caps which register with those in the laminations.

In the cap 14 is an insulating bushing 20 through which passes the cable 21 containing the high voltage leads 22. In use this 80 cable usually leads to a lamp socket or other suitable electrical outlet.

The cap 15, at the other end, has the insulating member or terminal board 23 which has therein the three terminals 24, 25 and 85 26 disposed at the apices of an equilateral triangle symmetrically disposed with respect to the centre of the cap, to which terminals are connected the taps or leads 27 leading from the low voltage winding. The 90 terminal board 23 shown comprises inside and outside insulating plates, shaped in clover-leaf fashion, having openings through substantially the centre of each of the three lobes. The insulating plates thus formed 95 bush larger openings similarly placed in the cap 15 as shown at 28, such plates being preferably formed in place by dies pressing the same up from suitable insulating compound which has been applied thereto.

100 The terminal 24 consists of a threaded screw with square head 30 which passes through a conducting clip 31 having a rolled edge 32 at one side, the other side being a straight edge. The rolled edge is anchored against a ledge 33 formed in the inner side of the inner plate of the terminal board 23. The head 30 fits snugly against the edge 32 so that it cannot turn. In this manner the 105 terminal 24 is securely stayed in its termi- 110

nal board and has on its outer end a washer and thumb nut 35 and 36 respectively which are adapted to engage with and hold in place the exterior conductor which is to lead 5 therefrom.

The terminal 25 is similar to terminal 24 in every respect but the screw of terminal 26 is larger than either that of 24 or 25. I 10 find the use of an odd sized terminal of advantage where it is desired to insure the selective attachment of leads thereto. For example, suppose across terminals 24 and 25 there is a difference of potential of 14 volts as indicated by the legend 14^v in Fig. 2; 15 suppose further that across terminals 25 and 26 there are 24 volts, and across terminals 26 and 24 there are 10 volts. Now if the terminals 24 and 25 are particularly adapted to a service where it is desired chiefly of the 20 transformer to supply a small lamp circuit of 14 volts, the leads would then be provided with washer clips having perforations therein of sufficient diameter to embrace only terminals 24 and 25, the clips being spaced 25 apart a distance adapted to fit across this pair of terminals, thereby preventing their fitting across any other pair.

In Fig. 4, I have shown an end cap having stamped out insulating plates of hard 20 fiber or similar material, instead of using the molded ones to bush the terminals in the cap 15 shown in Fig. 1. An insulating plate, as shown at 43 in Fig. 6, is stamped out in clover-leaf form which with a similar one 25 43' is adapted to support the terminals 24, 25 and 26 rigidly in proper relation; the heads of each screw being provided with a small prong 45 which is adapted to gouge into and hold such screws against rotation, 40 which would otherwise twist them loose from the leads from the winding.

Having now described an embodiment of my invention which is the best means at present known to me for carrying the same 45 into effect, I would have it understood that this is merely illustrative and that I do not mean to be limited thereby to the precise details shown, nor restricted in the choice of recognized equivalents except as defined in 50 my claims hereunto annexed.

What I claim as new and desire to secure by Letters Patent of the United States, is,—

1. In shell type induction apparatus, the combination with a core having windings thereon, of an end cap having a perforation, 55 a perforated insulating plate on each face of said end cap, a binding post passing through the perforations in said plates and cap, the inner end of said binding post having a non-circular head, and a clip under 60 the head of said binding post and embedded in said inner insulating plate, said clip having an edge bent into engagement with one side of the head of said binding post to prevent rotation thereof. 65

2. In shell type induction apparatus, the combination with a core having windings thereon, of an end cap having a perforation, a perforated insulating plate on each face of 70 said end cap, a binding post passing through the perforations in said plates and cap, the inner end of said binding post having a non-circular head, and a clip under the head of 75 said binding post and embedded in said insulating plate, said clip having a hollow rolled edge in engagement with one side of the head of said binding post to prevent rotation thereof and to receive a winding terminal of said apparatus. 80

3. In shell type induction apparatus, the combination with a core having windings thereon, of an end cap having perforations therein disposed at the vertices of an equilateral triangle, clover-leaf-shaped insulating plates pressed therein to bush said perforations, terminal binding posts secured in said 85 perforations, and means for anchoring said binding posts against rotation in said plates. 85

4. In shell type induction apparatus, the combination with a core having windings thereon, of an end cap having about the centre thereof at the vertices of an equilateral triangle, clover-leaf-shaped plates of insulating material pressed therein and arranged to bush said perforations, terminal binding 90 posts secured therein, and clips on the interior ends of said binding posts shaped both to anchor said terminals on said plates against rotation and to receive a winding lead. 95

In witness whereof, I have hereunto set my hand this 9th day of June, 1921.

VINCENT M. MONTSINGER.
